The ornamental design for a nestable structural hollow body, as shown and described.

DESCRIPTION

FIG. 1 is a top, front, left side perspective view of a nestable structural hollow body in a closed state showing my new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a top, front, left side perspective view of a nestable structural hollow body in an open state showing my new design.

FIG. 9 is a front elevation view thereof.

FIG. 10 is a back elevation view thereof.

FIG. 11 is a left side elevation view thereof.

FIG. 12 is a right side elevation view thereof.

FIG. 13 is a top plan view thereof.

FIG. 14 is a bottom plan view thereof; and,

FIG. 15 is a top, front, left side perspective view thereof shown in a stacked and nested configuration with a multiplicity of broken line nestable structural hollow bodies shown as environment forming no part of the claimed design.

The broken lines shown in the drawings are for environmental purposes only and form no part of the claimed design.
